LOCOMOTIVE STOKER

Eugene Martin, Erie, Pa., assignor to The Standard Stoker Company, Incorporated, a corporation of Delaware

Application March 4, 1937, Serial No. 128,892

11 Claims. (Cl. 110—104)

This invention relates to locomotive stokers of the type which feed fuel through an opening in the locomotive firebox backwall. More particularly, the present invention relates to certain improvements in locomotive stokers which are adapted to feed through a firing opening of conventional size and shape as found on many existing hand-fired locomotives.

It is the principal object of this invention to provide new and improved stoker means for feeding fuel through the opening in a locomotive firebox backwall, which means includes an arrangement of parts permitting free access to interior of the firebox through said opening.

15 A further object of this invention resides in the provision of a stoker which includes distributing means at the firing opening extending to a point forward of the outer surface of the firebox backwall, a conveyor for urging fuel to said distributing means, and fuel deflecting means between said conveyor and distributing means comprising a pair of independently operable vanes extending into the firing opening, such vanes being operable across said firing opening to control the flow of fuel to said distributing means and being retractable to a position adjacent the sides of said firing opening.

20 A still further object of this invention contemplates adapting the fuel guiding means to a stoker feeding through an elliptically shaped opening of conventional size and shape.

25 It is also an object of this invention to provide novel fuel guiding vanes which are mounted for pivotal movement about an axis extending in the direction of fuel through the stoker.

It is also an object of this invention to provide a fuel supporting surface within the firing opening and across which fuel supporting surface the lower edge of each guide vane operates, such 30 fuel supporting surface being shaped to allow the preponderant mass of fuel usually conveyed along its central portion to spread laterally, thereby securing a normally uniform delivery of fuel to the distributing means.

45 Other objects reside in the particular mounting of the fuel guide vanes, the means for adjusting them in various positions in the firing opening, and the novel relation of parts one with another for producing a stoker which occupies very little space in the cab and one which may be cheaply installed on existing hand-fired locomotives.

50 These objects and the advantages to be derived therefrom will become apparent upon reading the

following description in connection with the accompanying drawings, in which,

Fig. 1 is a central vertical section taken longitudinally through the backwall of a locomotive firebox showing the stoker embodying this invention partly in similar section and partly in side elevation;

Fig. 2 is a rear elevation of the structure shown in Fig. 1, with parts removed;

Fig. 3 is a sectional view taken on the line 3—3 of Fig. 1 with parts removed;

Fig. 4 is a sectional view taken on the line 4—4 of Fig. 1; and

Fig. 5 is an enlarged sectional view taken on the line 5—5 of Fig. 2.

On these drawings, 10 represents a locomotive, 11 the boiler thereof and 12 the hollow backwall including the outer sheet 13 and the inner sheet 14. At a suitable distance above the cab deck 15 and the grates 16 of the firebox 17, the inner and outer sheets are flanged inwardly toward each other to form the conventional firing opening 18. This firing opening is usually elliptical in shape and measures approximately sixteen (16) inches in height and twenty (20) inches in width, thereby affording free and unobstructed entry into the firebox. It is, of course, understood that in some instances these dimensions will vary.

The stoker for transferring fuel from the tender (not shown) to the locomotive is indicated by 8 and comprises a fuel elevator 19 on the locomotive, and a conveyor 20 which is flexibly connected to the lower end of the elevator 19 below the cab deck 15 by a ball and socket joint 21. The elevator 19 comprises a tubular conduit 22 which is secured to a bracket 23 carried by the backwall 12, and a fuel delivery conduit 24 secured to the backwall 12 by bolts 25 passing through the laterally extending flanges 26. Fuel is urged upwardly through the elevator 19 by a conveyor screw 27 disposed mainly within the tubular conduit 22 and having a tapered forward portion 27a within the conduit portion 28 of the delivery conduit 24. At their juncture, the tubular conduit 22 and the conduit portion 28 are provided with flanges 22a and 28a, respectively, arranged in abutting relation and through which flanges bolts 29 are passed for securing the tubular conduit 22 to the delivery conduit 24.

The conduit portion 28 opens upwardly into a casing 30 having an arcuate top wall 31 and curving side walls 32, the outer marginal edges 33 of which walls, together with the upper edge of the conduit portion rearward wall 38, define an

aperture 34 opposite the firing opening 18. A firedoor 35 is supported from the casing 30 upon pintles 36 and forms a movable closure for the aperture 34. Since the firedoor illustrated is of the well known "Franklin Butterfly" type, further description thereof is not deemed necessary, except to state that this door may be operated by power or manual means.

In order that the casing 30, and consequently the firedoor 35, may not extend an objectionable distance rearward of the backwall 12, the forward wall 37 and the rearward wall 38 of the conduit portion 23 converge toward each other in forward extent. The side walls 39 of this conduit portion flare outwardly in forward extent to provide a somewhat elliptically shaped aperture 40 which opens into the casing 30. Within the casing 30, and as a forward and upward extension of the conduit portion rearward wall 38, is a guide plate 41 which is hinged upon a long pin 42 extending across the upper edge of said conduit rearward wall 38. The guide plate 41 is moved to the position shown in Fig. 1 by the fuel stream entering the casing 30, further rearward movement of said guide plate 41 from that shown being prevented by a lug 32a extending inwardly from each side wall 32 of said casing. It will thus be apparent that the guide plate 41 prevents coal within the casing 30 from spilling on the cab deck 15 when the firedoor 35 is opened to inspect firebox conditions. Whenever access to the interior of the firebox is desired, the guide plate 41 may be lowered over the aperture 40.

Fuel enters the casing 30 through the aperture 40 and is then urged forwardly to a fuel distributor 43 positioned at the firing opening 18. The fuel distributor 43 consists of a pressure fluid jet member 44 which is secured, at its rearward end outside the firebox backwall 12, by bolts 45 to the forward wall 37 of the conduit portion 23. The jet member 44 forms a delivery plate over which fuel is urged forwardly. From its rearward end outside the firebox backwall 12 the jet member 44 extends forwardly through the lowermost portion of the firing opening into the firebox 17, being provided at its forward terminal 46 with jet openings 47. These jet openings discharge fluid under pressure, supplied by pipes 48 to the jet chambers 49, across the upper surface 50 of the distributing table 51 which is carried by the jet member 44 in a manner well known.

In order to control the flow of fuel across the upper fuel supporting surface 44a and into the zone of action of the distributor jet member 44, novel fuel guiding means is provided which is especially adaptable for use in connection with stokers feeding through a firing opening of conventional shape and size. This guiding means includes a pair of vanes 52, 53, one at each side of the firing opening 18 and positioned to act upon the fuel stream prior to the action thereon of the distributor jet member 44. Each vane 52, 53 is pivotally mounted upon a pin 54 carried by the casing 30 rearward of the backwall 12 and above the confines of the firing opening 18. The pins 54 extend longitudinally of the locomotive boiler permitting movement of each vane 52, 53 about an axis extending longitudinally of the locomotive.

Each vane 52, 53 extends into the firing opening 18 and the side of each vane is shaped to conform to the sides of the elliptical firing opening 18 whereby they may be retracted to a position closely adjacent said firing opening to provide maximum clearance for entrance into the

firebox 17. The lower edge of each vane 52, 53 is arranged to move across the fuel supporting surface 44a of the jet member 44, and since each lower edge moves in an arc described from the axis of a respective pin 54, the upper surface 44a is similarly formed leaving an elevated portion 55 in the central zone of said upper surface 44a. This elevated central portion 55 will be found of advantage in spreading laterally the preponderant mass of fuel usually passing across the jet member 44.

At the rearward end of each vane 52, 53 is a lateral outward extension 52a, 53a, respectively, fitting against the inner side of the flanges 26 which are hollowed as shown in Fig. 3 to accommodate these extensions. The extensions 52a, 53a serve to maintain a seal between the inner side of the flanges 26 and the backwall 12 to prevent loss of fuel when vanes 52, 53, respectively, are moved inwardly across the jet member 44.

Below the casing 30, each vane 52, 53 is provided with means for conveniently adjusting the angular position of each vane independently and also for locking each vane in its adjusted position. For this purpose, the lower end 52b, 53b of each extension 52a, 53a, respectively, has secured therein a pin 61 which extends rearwardly of the flange 26 and upon which pin a handle 56 is mounted to slide therealong against the tension of a spring 57 which is positioned between the head 58 of the pin 61 and the forward end 59 of the handle 56. The forward end of the handle 56 is somewhat reduced in diameter and is arranged to fit into an arcuate scalloped slot 60 formed in the flange 26. Each scalloped slot 60 is formed by providing a series of holes along an arc described from the center of a respective pin 54, the centers of the holes in each series being spaced apart along this arc at a distance less than the diameter of each hole.

In the operation of this device, fuel enters the casing 30 through the aperture 40 and is restrained against rearward movement by the guide plate 41. Thence, the fuel passes across the upper surface of the jet member upon which it spreads laterally due to the elevated central portion 55. If, because of uneven draft or for other reasons, it is desired to supply more or less fuel to one side of the firebox, the fireman grasps the handle 56 and withdraws its forward end 59 from the scalloped arcuate slot 60. Then the handle is swung to the right or left, as the particular situation demands, and upon reaching the desired angular position, the handle 56 is moved forwardly to cause the forward end 59 thereof to engage a new position in the scalloped slot 60. This causes the lower edge of a respective vane 52, 53 to move inwardly or outwardly across the upper surface 44a of the jet member 44, thereby forming in effect an expandible and contractible discharge outlet for fuel before its passage into the zone of action of the jet member 44. Upon falling over the forward terminal 46, the fuel is projected forwardly by blasts of pressure fluid issuing from the jets 47. Ribs 62 on the upper surface of the distributing table 51 direct the fuel to all parts of the firebed.

From the foregoing, those familiar with the art will understand that the stoker constructed according to this invention feeds fuel through the conventional firing opening, occupies but a small amount of space above the cab deck, and that the novel fuel deflecting means is effective to control the flow of fuel to the distributor. It will be fur-

ther apparent that since the guide vanes 52, 53 are constructed and arranged for retraction closely adjacent the sides of the firing opening, they do not form obstructions to the free entry 5 into the firebox.

I claim:

1. In combination with a firebox having an upstanding wall provided with a firing opening and a grate below the level of said firing opening, a stoker for feeding fuel into said firebox comprising a conduit in communication with said firing opening, means for urging fuel through said conduit and into said opening, a delivery plate extending forwardly from said conduit, means forward of said delivery plate for projecting fuel over the firebox grate, the upper surface of said delivery plate constituting a support for the fuel urged therealong, and means for deflecting fuel laterally across the upper surface of said plate 15 comprising a pair of guide vanes arranged for movement across the upper surface of said plate, each of said vanes being mounted for angular adjustment about an axis disposed above the upper surface of said member and extending approximately parallel to such surface, the lateral portion at each side of such surface being in the form of a cylindric element described from the axis of a respective vane.
2. In a stoker for a firebox having a wall with an opening therein, a stoker fuel feeding conduit communicating with said opening, means for advancing fuel through said conduit, a plate-like member at the discharge end of said conduit having a fuel supporting upper surface, a concave recess formed in the fuel supporting surface of said plate-like member adjacent each lateral extremity thereof and a pair of laterally spaced longitudinally extending fuel guiding elements mounted to turn about longitudinally extending axes disposed above said fuel supporting surface, the axes of said fuel guiding elements being so disposed with respect to said recesses that upon turning of the said guiding elements portions thereof pass across the surfaces defining said recesses.

3. In a stoker for a firebox having a wall with an opening therein, a stoker fuel feeding conduit communicating with said opening, means for advancing fuel through said conduit, a plate-like member at the discharge end of said conduit having a fuel supporting upper surface, a longitudinally elongated concave recess formed in the fuel supporting surface of said plate-like member adjacent each lateral extremity thereof and a pair of laterally spaced longitudinally extending fuel guiding elements mounted to turn about longitudinally extending axes disposed above said fuel supporting surface, the axis of said fuel guiding elements being so disposed with respect to said recesses that upon turning of the said guiding elements portions thereof pass across the surfaces defining said recesses.

4. In a stoker for a firebox having a wall with an opening therein, a stoker fuel feeding conduit communicating with said opening, means for advancing fuel through said conduit, a jet head at the discharge end of said conduit having a fuel supporting upper surface, a longitudinally elongated concave recess formed in the fuel supporting surface of said jet head adjacent each lateral extremity thereof and a pair of laterally spaced longitudinally extending fuel guiding elements mounted to turn about longitudinally extending axes disposed above said fuel supporting surface, the axes of said fuel guiding elements

being so disposed with respect to said recesses that upon turning of the said guiding elements portions thereof pass across the surfaces defining said recesses.

5. In a stoker for a firebox having a wall with an opening therein, a stoker fuel feeding conduit communicating with said opening, means for advancing fuel through said conduit, a plate-like member at the discharge end of said conduit having a fuel supporting upper surface, a concave recess formed in the fuel supporting surface of said plate-like member adjacent each lateral extremity thereof and a pair of laterally spaced longitudinally extending fuel guiding elements mounted to turn about longitudinally extending axes disposed above said fuel supporting surface, each of said concave recesses being described from the axis of a respective fuel guiding element, a portion of each of said fuel guiding elements fitting closely against the surface defining a respective recess.

6. In a stoker for a firebox having an upstanding wall provided with a firing opening, a stoker fuel feeding conduit communicating with said firing opening, means for urging fuel through said conduit, a member at the discharge end of said conduit having a surface along which fuel is urged to the firebox, and a pair of longitudinally extending laterally spaced fuel guiding elements mounted to swing about longitudinally extending axes, said guiding elements being arranged to have their free ends in close proximity to the said surface of said member, and said surface being curved to conform to the path described by the free ends of said guiding elements when swung about their longitudinally extending axes.

7. In a stoker for a firebox having an upstanding wall provided with a firing opening, a stoker fuel feeding conduit communicating with said firing opening, means for urging fuel through said conduit, a member at the discharge end of said conduit having a fuel supporting upper surface across which the fuel is urged to the firebox, and a pair of longitudinally extending laterally spaced fuel guiding elements mounted to swing about longitudinally extending axes disposed above said fuel supporting surface, said guiding elements being arranged to have their free ends in close proximity to said fuel supporting surface, and said surface being curved to conform to the path described by the free ends of said guiding elements when swung about their longitudinally extending axes.

8. In combination, a firebox having an upstanding wall provided with a firing opening, a stoker comprising a fuel feeding conduit communicating with said firing opening, means for urging fuel through said conduit, a member at the discharge end of said conduit having a surface along which fuel is urged to the firebox, and a pair of longitudinally extending laterally spaced fuel guiding elements extending into said firing opening and mounted to swing about longitudinally extending axes, said guiding elements being arranged to have their free ends in close proximity to the said surface of said member, said surface being curved to conform to the path described by the free ends of said guiding elements when swung about their longitudinally extending axes and said vanes being curved to fit closely against the sides of said firing opening.

9. In combination, a firebox having an upstanding wall provided with a firing opening, a stoker comprising a fuel feeding conduit communicating with said firing opening, means for urging fuel

- through said conduit, a member at the discharge end of said conduit having a fuel supporting upper surface across which the fuel is urged to the firebox, and a pair of longitudinally extending laterally spaced fuel guiding elements extending into said firing opening and mounted to swing about longitudinally extending axes disposed above said fuel supporting surface, said guiding elements being arranged to have their free ends in close proximity to said fuel supporting surface, said surface being curved to conform to the path described by the free ends of said guiding elements when swung about their longitudinally extending axes and said vanes being curved to fit closely against the sides of said firing opening.
10. In a stoker for a firebox having an upstanding wall provided with a firing opening, a stoker fuel feeding conduit communicating with said firing opening, means for urging fuel through said conduit, a member at the discharge end of said conduit having a surface along which fuel is urged to the firebox, and a pair of longitudinally extending laterally spaced fuel guiding elements mounted to swing about longitudinally extending axes, said guiding elements being arranged to have their free ends in close proximity to the said surface of said member, said surface being curved to conform to the path described by

the free ends of said guiding elements when swung about their longitudinally extending axes, and flanges formed with and extending laterally from the rearward ends of said guiding elements to form a fuel seal between said conduit and said 5 guiding elements.

11. In a stoker for a firebox having an upstanding wall provided with a firing opening, a stoker fuel feeding conduit communicating with said firing opening, means for urging fuel through 10 said conduit, a member at the discharge end of said conduit having a fuel supporting upper surface across which the fuel is urged to the firebox, and a pair of longitudinally extending laterally spaced fuel guiding elements mounted to 15 swing about longitudinally extending axes disposed above said fuel supporting surface, said guiding elements being arranged to have their free ends in close proximity to said fuel supporting surface, said surface being curved to conform to 20 the path described by the free ends of said guiding elements when swung about their longitudinally extending axes, and flanges formed with and extending laterally from the rearward ends of said guiding elements to form a fuel seal be- 25 tween said conduit and said guiding elements.

EUGENE MARTIN.
